UNITED STATES PATENT OFFICE.

GEORGE E. KANNEMANN, OF WOODBURY, NEW YORK,

FLAGPOLE HOLDER FOR GOLF COURSES.

Application filed April 18, 1928. Serial No. 270,865.

This invention relates generally to flag pole holders and has more particular reference to a novel golf course pole holder.

The invention has for an object the provision of a device of the class mentioned, which is of simple, durable construction, desirable and efficient in action and which can be manufactured and sold at a reasonable cost.

10 The device proposes the use of a bushing arranged for connection on the bottom of a golf pole, and provided with a shoulder and a lower reduced portion for engaging in an opening within a golf hole bracket so as to 15 firmly and positively hold the pole in vertical position. A means may be provided for insuring a good connection between the said bushing and the golf hole bracket.

This arrangement, quite obviously, is far 20 superior to the common method of forcibly driving a pointed peg usually arranged on the bottom of a golf pole thru a hole in the golf hole bracket and into the ground. Very often during this driving the golf pole 25 splits and breaks, and besides great difficulties arise in that the golf pole refuses to remain in a vertical position and leans towards one side, due to soft ground or loose connections between the peg and the ground. 30 For further comprehension of the invention, and of the objects and advantages thereof, reference will be had to the following description and accompanying drawings, and to the appended claims in which the various novel features of the invention are 35 more particularly set forth.

In the accompanying drawing, forming a material part of this construction:—

Fig. 1 is a vertical sectional view of a golf 40 hole bracket, and a golf pole engaged therein according to this invention.

Fig. 2 is a plan view of the bracket, per se.

Fig. 3 is a side elevational view of a golf 45 pole, and a bushing as used in this invention engaged thereon, the bushing being shown in section.

Figs. 4 and 5 are similar views of different golf poles.

Fig. 6 is a perspective view of the bushing, per se.

Fig. 7 is a side elevational view of a bushing of modified form, a portion thereof being broken away to disclose the interior construction.

55 The reference numeral 10 indicates generally the tubular body of a golf hole bracket,

provided with a cup shaped member 11 presenting an opening 12. This cup shaped member is connected with the tubular body by means of substantially horizontal ribs 13 60 and vertical ribs 14. The bottom of the cup shaped member 11 has an aperture 15 for permitting the bottom pegs of golf poles to pass thru and engage in the ground. In the instant invention this aperture is not used 65 for this purpose, but serves as an outlet for rain water.

A wooden golf pole 16 is formed with a reduced lower end 17 upon which metallic rings 18 and 19 are engaged. A metallic 70 bushing 20 engages upon these rings and is thus held by a screw 21. The bushing 20 is formed with a shoulder 22 and a lower reduced portion 23. As shown in Fig. 1, the shoulder 22 rests upon the cup 11, and the reduced portion 23 snugly engages in the cup opening 12, for firmly and positively holding the pole in vertical position. 75

The golf pole 24 illustrated in Fig. 4, is a metallic one, and has an enlarged bottom portion 25 and a ring 26 on the main portion of the pole. The bushing 20 is engaged upon the portion 25 and the ring 26 in a manner similar to the one just described relative to golf pole 16. In Fig. 1 dot dash lines 24' 80 simulate this pole. Since the pole 24 is thinner than pole 16, a golf ball may enter the golf ball bracket 10 easier when the thinner pole is used. 85

In Fig. 5 a bamboo golf pole 27 is illustrated provided with the same bushing 20, and in Fig. 6 a detail perspective view of the bushing itself has been shown. 90

The modified form illustrated in Fig. 7, shows a bushing 20' provided with an attaching screw 21, a shoulder 22, and a bottom tapered member 23'. Wedge members 28 are formed with dovetailed tongues 29 slidably engaging grooves in the sides of the tapered member 23'. Pins 30 project from the wedge members 28 and into slots 31 formed in the tapered member 23' for holding the wedges against displacement. In operation the wedge members 28 engage in the cup 12 and are spread outwards firmly against the sides of the cup by downward motion of the bushing 20'. 100 105

While I have illustrated and described the preferred embodiment of my invention, it is to be understood that I do not limit myself to the precise construction herein disclosed and the right is reserved to all changes and 110

modifications coming within the scope of the invention as defined in the appended claims.

Having thus described my invention, what I claim as new, and desire to secure by United States Letters Patent is:—

1. A bushing for a device of the class described, comprising a main portion arranged for connection with a golf pole, and a shoulder and reduced portion connected therewith and provided with wedge members slidably mounted and being capable of snugly engaging in a cup opening of a golf hole bracket for holding an engaged golf pole in a vertical position.
- 10 2. A bushing for a device of the class described, comprising a main portion arranged for connection with a golf pole, and a shoulder and reduced portion connected therewith and provided with wedge members slidably mounted by reason of dovetailed tongues from the wedge members engaging in grooves in the reduced portion, and the wedge members being capable of snugly engaging in a cup opening of a golf hole bracket for holding an engaged golf pole in a vertical position.
- 15 3. A bushing for a device of the class described, comprising a main portion arranged for connection with a golf pole, and a shoulder and reduced portion connected therewith and provided with wedge members slidably

mounted by reason of tongues engaging in grooves, and the wedge members being capable of snugly engaging in a cup opening of a golf hole bracket for holding an engaged golf pole in a vertical position.

4. A bushing for the class described, comprising a main portion arranged for connection with a golf pole, a shoulder and reduced portion connected therewith and provided with wedge members slidably mounted and being capable of snugly engaging in a cup opening of a golf hole bracket for holding an engaged golf pole in a vertical position and pins projecting from the wedge members and engaging slots formed in the said reduced portion for holding the wedge members to limited movements.

5. A bushing for a device of the class described, comprising a main portion arranged for connection with a golf pole, a shoulder and reduced portion connected therewith and provided with wedge members slidably mounted and being capable of snugly engaging in a cup opening of a golf hole bracket for holding an engaged golf pole in a vertical position, and a means for holding the wedge members to limited movements.

In testimony whereof I have affixed my signature.

GEORGE E. KANNEMANN.
